(57) **CLAIM**

The ornamental design for fastening, supporting or mounting device, as shown and described.

DESCRIPTION

FIG. 1 is a perspective view of a fastening, supporting or mounting device showing our design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a bottom plan view thereof; and,

FIG. 7 is a top plan view thereof.

The broken lines in the figures are for illustration purposes only and form no part of the claimed design.
